TYPE-WRITER MANIFOLD ATTACHMENT.

1,092,115.

Specification of Letters Patent. Patented Mar. 31, 1914.

Application filed July 5, 1913. Serial No. 777,557.

To all whom it may concern:

Be it known that I, THEODOR NORPOTH, citizen of the United States, residing at St. Louis, State of Missouri, have invented certain new and useful Improvements in Type-Writer Manifold Attachments, of which the following is a full, clear, and exact description, reference being had to the accompanying drawings, forming a part hereof.

10 My invention has relation to improvements in type-writer manifold attachments; and it consists in the novel features of construction more fully set forth in the specification and pointed out in the claims.

15 In the drawings, Figure 1 is a perspective of a type-writer showing the application of my invention thereto; Fig. 2 is a front elevation of the upper end of the oscillating frame carrying the driving gear for the rollers;

20 Fig. 3 is a side elevation of the attachment; Fig. 4 is a vertical section on the line 4—4 of Fig. 1; Fig. 5 is a horizontal section on the line 5—5 of Fig. 3; Fig. 6 is a detail showing a face view of the outer gear wheel and pawl engaging the spring-winding ratchet; Fig. 7 is a similar view of the inner gear-wheel or that to which the outer end of the driving spring is attached, the shaft or winding arbor being shown in cross-section

25 in both views 6 and 7; Fig. 8 is a sectional detail on the line 8—8 of Fig. 2; and Fig. 9 is a detail in side view of a modified form of blade-rocking mechanism.

30 The object of my invention is to provide any type-writing machine with a manifold attachment adapted to be applied to the reciprocating carriage on which the roller or platen is mounted, said attachment being characterized by certain distinguishing features, among which may be mentioned, a web of carbon or manifold paper operating in conjunction with the usual letter sheets; a roll of copy paper or sheet on which the copy of the original is made; a cutter by

35 which the copy sheet may be severed into predetermined lengths; means for permitting the preservation of all the copies on a single web or roll; a spring-driving or actuating mechanism responsive to the periodic advances of the main roller or platen; and other structural features the advantages of which will be more clearly apparent from a detailed description of the invention which is as follows:

40 Referring to the drawings, and for the present to Figs. 1 to 8 inclusive, T represents a conventional form or make of type-writing machine, C the reciprocating carriage thereof, and R the roller or platen over which the letter sheets L are passed and against which the type-bars operate, all as well understood in the art. In the present embodiment of my invention, I secure to the carriage in any mechanical manner a relatively stationary horizontal frame F, said frame in the illustration being provided with depending legs or members F' at the inner or front corners thereof to effect connection with the carriage, said legs being in the present instance made preferably integral with the terminals of the carriage, whereby the frame F likewise becomes an integral part of the carriage. Mounted across the medial portion of the frame F about an axis parallel to the axis of the roller R is a roll of copy paper or sheet 1, the free end of which is brought forward over the spring guides a on the machine and over the roller R, thence rearward over a guide, or forwardly and downwardly inclined curved supporting apron 2 secured at 45 its upper fixed end to the front face of a flat metal strip or bar 3 set on an incline, and provided with forwardly bent terminal arms 3', 3', secured to lugs e formed on the frame F. Mounted between the arms 3', 3', and 50 spaced from the apron 2, is a rock-shaft 4 which projects at each end a suitable distance outside and beyond its points of support in said arms 3', and is provided with a crank-arm 5 at each end. Secured to the 55 rock-shaft 4 between the members 3', 3', and extending substantially the full length of the strip 3 is a cutter or blade 6 disposed in a plane at an obtuse angle to the plane of disposition of the crank-arms 5, 5, the latter by 60 reason of their leverage and weight (as against that of the blade) normally dropping to substantially a horizontal position and resting against the offsets h, h, formed in the frame F. I do not wish however, to 65 limit myself to the obtuse angle here referred to. With the crank-arms 5 in their lowest or horizontal position, the shaft 4 will be rocked so as to oscillate the blade 6 sufficiently to clear the upper edge of the 70 apron 2 (Figs. 3, 4) thereby leaving a clear space for the free and uninterrupted travel therethrough of the sheet 1 after leaving the apron 2, and as it passes onto and over the upper flexed guide strips 7, 7, overhanging 75

the roller 1 (and the roller S rearward thereof to be presently referred to), the fixed ends of said strips 7 being secured to the rear face of the strip or bar 3. Mounted rearward of the roll 1 is a roll of carbon or equivalent manifold paper 8, the roll 8 being parallel to the roll 1, the sheet therefrom being likewise brought forward over the springs or guides a, between said guides and the sheet 1, whence the sheet 8 is brought over the roller R in front of the sheet 1 and between the latter and the usual original or letter sheet L against which bears the ink ribbon 7 through which the impressions on said sheet L are made as well understood in the art. The sheet L must obviously be inserted from rear forwardly, between the guides a, and roller R, so that the sheet 8 will come between the sheets L and 1. As well understood in the art rolls on the order of 1 and 8 are usually provided with roller core pieces or cylinders P and S, respectively, terminating in spindles 10, 10. In the present mounting the spindles 10 have bearing 25 against them the free ends of suitable spring arms 11, 11, whose fixed ends are secured to the frame F, said springs operating as brakes to prevent the rolls from turning too freely, and hence at all times imposing the proper 30 tension on the sheets as they are drawn through the machine. The free ends of the springs 11 terminate in loops 11' by which they may be manipulated to release the spindles. In front of the machine the several 35 sheets pass between the roller or platen R and a guide roller m already present in the machine, the sheets 1 and 8 separating and being independently guided after leaving the roller m and platen R.

Pivoted between the sides of the frame F in front of the offsets h, h, is an oscillating frame N in the form substantially of an inverted U, the arms of said oscillating or tilting frame having formed suitable offsets 45 n, n, at points adjacent the pivotal axis of the frame. To the opposite faces of these offsets are secured the fixed ends of the tripping arms or tappets 12, 13, respectively, the lower arms 13 being the longer and terminating in upturned hooks 13' as shown, each pair of arms (12, 13) being disposed substantially in the same vertical plane. When the frame N is oscillated rearwardly the arms 12 bear against the crank-arms 5 of the 50 rock-shaft 4 of the blade 6, thereby arresting any further rearward oscillation of the frame and likewise preventing accidental depression or rearward oscillation of the blade; and when the frame N is oscillated forwardly 55 the arms 13 (which diverge at a suitable angle from the arms 12) trip the crank arms 5 upwardly (see dotted position Fig. 4) thus rocking the shaft 4 in proper direction to cause the blade 6 to oscillate rearwardly and 60 bring the cutting edge of said blade in firm

contact with the sheet 1 and the upper edge of the supporting apron 2 over which said sheet passes on its way to the flexed guides 7, 7. The forward or outward oscillation of the frame N is limited by the hooks 13' which 70 grasp the ends of the already elevated crank-arms (Fig. 4, dotted position).

Mounted detachably on the frame N in any well known manner known to the art for mounting rollers, is a roller S' corresponding to the core S of the carbon paper roll 8; the sheet 8 after leaving the platen R passing over said roller S' and winding the sheet 8 thereon as fast as the same unwinds from the core S, the sheet passing 80 over an intermediate roller or idler 14 as shown. As well understood in the art the sheets L, 8 and 1 are advanced through the machine by the periodic advances or rotations of the roller or platen R, the amount 85 or degree of advance depending on the size of spacing between consecutive lines. So far as the sheets L and 1 are concerned, these are fed through the machine by the periodic rotations of the roller R accomplished manually by the operator manipulating the type-writer; but the carbon paper sheet 8 which is used until no longer available must be wound on the roller S' as it unwinds from the core S. To impart to the 90 roller S' a rotation which shall respond to the periodic advances of the sheet 8 by the roller R, some provision must be made to drive the roller S'. This is accomplished by the following mechanism:—On the right 95 hand side of the frame N is a spring actuated clock mechanism mounted in a housing or frame W, (which by the way serves to support the spindles s', 14', of the rollers S' and 14 respectively). In said housing is 100 mounted a shaft or winding arbor 15 adapted to be manipulated by a key K, said shaft having keyed thereto a ratchet pinion 16 with which cooperates a spring-controlled pawl 17 pivoted to the adjacent face of a 105 gear wheel 18 mounted loosely on the shaft adjacent to the ratchet pinion, a second gear 19 at the opposite end of the shaft being likewise mounted loosely on said shaft. Between the gears 18, 19 is a driving spring 110 20 whose inner end is secured to the shaft, the outer end being secured to the adjacent face of the wheel 19. The wheel 18 meshes with a pinion 21 on the spindle s' of the roller S', the gear 19 in turn meshing with a 115 pinion 22 on the spindle 14' of the roller 14. From the connections described it will be seen that when the spring 20 is wound (the winding being accomplished by turning the arbor or shaft 15 clockwise by means of the 120 key K), it will drive the gear 18 in one direction (Fig. 6) and the gear 19 in the opposite direction (Fig. 7) the respective gears being loose on the shaft 15. Of course, the gear 18 being connected to the ratchet 125 130

through the pawl 17 will naturally move in unison with the shaft 15 as the latter "unwinds" under the influence of the drive-spring 20. The gears 18, 19, thus turning in opposite directions will impart rotations in opposite directions respectively to the rollers S' and 14 (Fig. 4). Either gear 18, 19, may be locked against rotation through the medium of a tooth or process w, on a slide 10 or brake-bar 23 polygonal in cross-section sliding through a corresponding opening in the side of the frame N, an inward movement of the slide forcing the tooth w across the space between consecutive teeth on the gear and hence lock the gear against rotation. The outer ends of the slides 23 are provided with finger-holds 23' for manipulating the same. In Fig. 2 it will be seen that the gear 19 is shown as locked against 20 rotation thus preventing the idler roller 14 from turning. The object of arresting either gear against rotation as here indicated will be brought out in the description of the operation of the device to be presently given. The axis of oscillation of the frame N being eccentric to the axis of the roller R over which the sheet 8 passes, it follows that when said frame is swung to its forward dotted position in Fig. 4 (to drive the cutting edge of the blade 6 against the apron 2), the roller S' will be at a greater distance from said axis (of the roller R) and consequently more or less tension will be exerted on the stretch of web or sheet 8 between the members R and S'. This tension or pull will naturally impart a rotation to the roller S' in a direction opposite to that in which it is normally driven by the spring 20, and against the tension of said spring, 40 but since the spring is not a powerful one, it will readily yield to the pull thus exerted on the web 8, the gear 18 and arbor 15 under the circumstances having imparted thereto a slight reverse rotation or in a direction opposite to that indicated by the arrow in Fig. 6 (see dotted arrow in dotted position of the parts in Fig. 4).

In lieu of the tripping members 12, 13, for rocking the shaft 4, I may provide the frame N with a toothed segment 24 engaging a pinion 25 on the rock-shaft 4' of the blade 6, as shown in the modification in Fig. 7. In that case the blade 6 is set at such an angle that by the time the frame N has 55 swung forward through an arc corresponding to what it describes in Fig. 4, the pinion 25 and shaft 4' will have rotated sufficiently to cause the edge of the blade to forcibly engage the upper edge of the apron 2, the frame N being arrested against any further oscillation forward by the arrest of the blade against the apron, the segment 24 remaining in permanent mesh with the pinion 25. A return of the frame N will of course, restore the parts to normal position

as indicated in said Fig. 9. In such return the frame is limited by the lug w striking the frame F.

The operation may be described by a reference to Figs. 1 to 8 inclusive, and is substantially as follows:—The original writing sheet or letter paper L is passed over the roller R from rear forward as usual (Figs. 3, 4), the webs 1 and 8 having been previously passed over the roller from their respective rollers P, S, in the order indicated on the drawings, that is to say with the carbon web 8 between the sheet L and web 1. The web 1 is conducted from the roller R rearward along the apron 2 and drawn through the slot or space between the cutter 6 and the upper edge of the apron so as to just project beyond the cutter. The web 8 is passed over the guide roller 14 and over the winding roller S'. With the periodic advances or rotations of the roller or platen R (done manually by the operator as well understood in the art) the several webs L, 8, 1, will be advanced accordingly; but inasmuch as in the present embodiment of my invention I employ a sheet of carbon paper which must be wound at one end as fast as it unwinds from its roller S at the other end, suitable provision must be made for an automatic winding thereof as the sheet is advanced by the roller R. This winding of the carbon sheet is accomplished by the turning of the roller S' under the driving action of the spring 20 as already described, the spring automatically taking up the slack of the sheet (8) with each advance thereof by the roller R, by the driving of the roller S' in the proper direction. The operation as described assumes that the gear 19 is locked against rotation by the tooth w of its corresponding slide or brake-bar 23 (Fig. 2) whereby the idle roller 14 remains stationary, the sheet 8 simply slipping over it. After a letter or other writing on the sheet L has been completed, the copy sheet 1, which by that time has been advanced a greater or less distance beyond the blade 6 and over the guides 7, 7, is torn off or severed by swinging the frame N forward to the dotted position indicated in Fig. 4, the oscillation of said frame in the direction indicated causing the arms 13 to trip the crank-arms 5, 5, upwardly and thus force the edge of the blade against said sheet 1 and against the upper edge of the apron 2. With the edge of the blade thus bearing against the copy sheet, a clean cut of the sheet may be made by simply drawing the sheet along the edge of the blade. The severed section thus contains a carbon copy of the letter or communication or other writing impressed on the sheet L, and may be filed away for future reference.

Should it be desired to preserve the carbon copies or manifolds on a single roll or

sheet, then, in lieu of passing the web 1 behind the blade or cutter 6, the same may be led over the roller 14 as shown by the dotted position of the sheet in Fig. 4. In 5 that event the gear 19 is released by disengaging the tooth *w* therefrom, leaving the spring to rotate the gear in the direction indicated by the arrow in Fig. 7. This will have the effect of turning the roller 14 10 counter-clockwise (see dotted arrow Fig. 4) whereby as the web 1 is periodically advanced by the roller R it will be automatically wound on the roller 14, and the entire record of all carbon copies be thus preserved 15 in roll form. The turning of the roller 14 and the winding thereon of the sheet 1 will in no wise interfere with the passage there-over of the sheet 8, the friction being insufficient to affect the free travel of said 20 sheet 8. Where the record of the carbon copies of letters is thus preserved in roll form, the occasion does not arise to tilt the frame N forwardly, the latter remaining in its rearwardly inclined position as indicated 25 in Figs. 3 and 4. After the carbon sheet 8 has been wholly unwound from the roller or core S and wound on the roller S', the rollers are removed from their respective 30 frames, after which the full roller S' is deposited on the frame F, and the empty roller S on the frame N, the carbon sheet being brought around so as to now wind on the roller S and unwind from the roller S'. In this way the same sheet of carbon 35 can be passed back and forth a number of times through the machine until the copying coating thereof is exhausted. In removing the rollers S, S', for the purpose of mounting the same to cause the web of 40 carbon paper to reverse its travel through the machine as indicated, the gear 18 is locked temporarily against rotation by shoving in the slide opposite thereto until the tooth *w* thereof locks with the teeth of the 45 gear wheel. Unless this were done, the spring 20 would unwind itself while the change in position of rollers was being made because there would be no resistance offered to the rotation of the gears. This unnecessary unwinding of course, is undesirable, and 50 for this reason the gear 18 is locked until the rollers S, S', are reset.

Where the cutter 6 is availed of for severing the copy sheet 1 at the end of each letter 55 written, the apron 2 supports the portion of the sheet which is beyond the roller R and below the section to be severed (which is beyond the cutter) so as to leave the free end of said portion substantially flush with 60 the upper edge of the apron; whence it will readily feed over the members 7, 7, with subsequent advances of the roller R.

I do not desire of course, to be limited to 65 the exact details here shown or be restricted in the application of the invention to any

particular make of typewriter, it falling within the purview of any skilled mechanic to adapt the attachment to any machine on the market. For purposes of the claims herein the frame F, F', may be considered 70 as a part of the carriage C.

Features shown but not alluded to are well known in the art and require no description in the present connection.

Having described my invention, what I 75 claim is:—

1. In combination with a type-writer carriage and its platen, means on the carriage for the support of sheets of manifold and copy material respectively, said sheets being adapted to be jointly passed over the platen, and advanced thereby, the copy sheet separating from the manifold sheet upon leaving the platen, means for guiding and supporting the copy sheet after its separation from the manifold sheet, a cutter 80 movably mounted adjacent said guiding and supporting means to co-operate therewith, a support pivoted to the carriage, means on said support for winding up the manifold 85 sheet, and means on said support for forcing the cutter toward said guiding and supporting means and into close contact with the copy sheet with a movement of said support in a given direction. 90

2. In combination with a type-writer carriage and its platen, means on the carriage for the support of sheets of manifold and copy material respectively, said sheets being passed over the platen and jointly advanced thereby, the copy sheet separating under the action of gravity from the manifold sheet upon leaving the platen, a supporting member for the copy sheet after its separation from the manifold sheet, an oscillating cutter positioned opposite the supporting member and normally spaced therefrom to allow the copy sheet to pass between it and the supporting member, a frame hinged to the support for the sheet material, means on said frame for winding up the manifold sheet, and means on said frame for oscillating the cutter against the copy sheet and its support with an oscillation of the frame in one direction, whereby 105 the copy sheet may be readily severed along the edge of the cutter. 110

3. In combination with a type-writer carriage and its platen, means on the carriage for the support of sheets of manifold and copy material respectively, said sheets being passed over the platen and jointly advanced thereby, the sheets separating under the action of gravity upon leaving the platen, a supporting member for the copy sheet after its separation from the manifold sheet, an oscillating cutter positioned opposite said supporting member, and normally spaced therefrom to allow for a free passage of the copy sheet, an oscillating frame 120

- hinged to the carriage about an axis eccentric to the axis of the platen, and means on said frame for oscillating the cutter against the copy sheet and its support with an oscillation of the frame in one direction, whereby the copy sheet may be readily severed along the edge of the cutter.
4. In combination with a type-writer carriage and its platen, means on the carriage for supporting rolls of manifold and copy material in sheet form in position to pass the sheets conjointly over the platen whereby they may be conjointly advanced by said platen, the sheets separating upon leaving the platen, a support for the copy sheet after its separation from the manifold sheet, a movable cutter normally spaced from said support and forming a passage-way therewith for the free traverse of the copy sheet, an oscillating frame mounted on the carriage, means on said frame for winding up the manifold sheet as the same is unwound from the roll supported on the carriage, means on said oscillating frame responsive to the platen advances for automatically actuating said winding means, and devices on said oscillating frame for driving the edge of the cutter against the copy sheet support whereby the sheet may be readily severed.
5. In combination with a type-writer carriage and its platen, means on the carriage for supporting rolls of manifold and copy material in sheet form in position to pass the sheets conjointly over the platen whereby they may be conjointly advanced thereby, the sheets separating upon leaving the platen, a frame mounted on the carriage, a roller on said frame for winding up the manifold sheet unwound from its roll supported on the carriage, a clock mechanism for driving said roller, a second parallel roller in mesh with the clock-mechanism and rotating in a direction reverse to that of the first roller, means for normally locking said second roller against rotation, said locked roller serving as a guiding roller or idler for the manifold sheet being wound on the first roller, said idler when released serving as a winding roller for the copy sheet where the latter is to be maintained in its integrity as it is unwound from its initial roll.
6. In combination with a type-writer carriage and its platen, means on the carriage for supporting rolls of manifold and copy material in sheet form in position to pass the sheets conjointly over the platen, the sheets separating upon leaving the platen, a support for the copy sheet after its separation from the manifold sheet, a movable cutter normally spaced from said support and forming a passage-way therewith for the free traverse of the copy sheet, a movable frame mounted on the carriage, means on said frame for winding up the manifold sheet after its separation from the copy sheet, and devices on said movable frame for driving the cutter against the copy sheet support, whereby the sheet may be readily severed.
7. In combination with a type-writer carriage and its platen, means for supporting rolls of manifold and copy sheets positioned to be passed about the platen, the sheets separating after passing the platen, an oscillating frame hinged to the carriage, a support for the copy sheet after its separation from the manifold sheet, a rock-shaft disposed parallel to said support and spaced therefrom, a blade on said rock-shaft, arms forming terminals for said rock-shaft, tripping members on the oscillating frame cooperating with said arms to cause the rock-shaft to oscillate and force the edge of the blade against the copy sheet and its support with an oscillation of the frame in one direction, means for limiting the swing of the frame when so oscillated, and means for arresting the swing of the frame in the opposite direction.
- In testimony whereof I affix my signature, in presence of two witnesses.

THEODOR NORPOTH.
